DESIGN FOR A HAT

Alys C. Moran, New York, N. Y., assignor to Hat Corporation of America, Norwalk, Conn., a corporation of Delaware

Application January 19, 1939, Serial No. 82,432

Term of patent 3½ years

To all whom it may concern:

Be it known that I, Alys C. Moran, a citizen of the United States, residing at New York, in the county of New York and State of New York, have invented a new, original, and ornamental Design for Hats, of which the following is a specification, reference being had to the accompanying drawing, forming a part thereof, and in which:

Fig. 2 is a side view of the hat shown in Fig. 1.

Fig. 3 is a fragmentary detail view showing the design of the crown.

Fig. 4 is a rear view of the hat shown in Fig. 1.

My design comprises a hat consisting of a crown portion composed of a spirally arranged felt strip superimposed on a ribbon base in combination with a felt brim portion, as shown.

I claim:

The ornamental design for a hat, substantially as shown and described.

ALYS C. MORAN.
